PACKAGING MACHINE

John H. Stroop, New York, N. Y., assignor to The
 Pad-Y-Wax Company, Inc., New York, N. Y.,
 a corporation of New York

Application October 29, 1951, Serial No. 253,641

22 Claims. (Cl. 53—84)

1

This invention pertains to packaging machines, and more particularly relates to a machine for enclosing tablets, capsules, lozenges or other articles between two webs of flexible, heat-sealable material, such as cellophane or material having a thermoplastic coating.

The present application is related to my copending application, which is now issued as Patent 2,608,809, September 2, 1952, wherein is disclosed a machine for continuously forming article-containing packages of two webs of flexible packaging material wherein the webs are fed between a pair of cooperating, continuously rotating sealing rollers having corresponding article-defining pockets peripherally spaced thereon. The articles to be packaged are fed through a hollow mandrel which reciprocates in timed relationship with the rollers and spreads the webs into the pockets thereon. The rollers are heated, and as the webs pass therebetween, they are sealed together except at localities corresponding to the pockets.

The articles are fed from a hopper onto a vibrating feed table which advances them toward and into the substantially horizontal, upper end of an arcuate duct. The articles then drop by gravity through the duct to the substantially vertical lower end thereof, on which the mandrel is carried, so that the duct and the mandrel reciprocate together. Also, at its lower end, the duct is provided with means operable in timed relationship with the reciprocation of the duct and the mandrel to regulate the flow of articles into the mandrel.

Such a machine may be provided with multiple packaging means. For example, it may be desired to produce packages having two parallel rows of article-containing pockets. The machine illustrated in said patent is of that type, with two ducts, two mandrels and two sets of pockets on each roller.

A machine as outlined above performs its functions very well and is in commercial use. However, as will be appreciated, it is not easily adaptable to packaging articles of varying sizes and shapes.

Accordingly, the present invention provides a machine having universal feeding means which is easily adjustable to accommodate articles of differing sizes and shapes, within predetermined limits.

At the same time the present invention discloses a machine of simpler and cheaper construction than the machine of said copending application, in that the reciprocating arcuate duct may be eliminated, and its place is taken and its

2

function performed by an inclined stationary tube or chute. Means may be included for adjusting the cross-sectional area and shape of the chute to provide the universal feeding means referred to above.

The mandrel, which is separate from the adjustable chute, reciprocates in a truly vertical path directly above the intersection of the sealing rollers.

10 The machine has the advantage of attaining higher operating speeds and thereby increasing its capacity to produce because the feed mechanism is relatively stationary and does not reciprocate with the mandrel and therefore the weight of the reciprocating parts is less than would otherwise be required.

20 Articles may be conveniently fed from a hopper into one end of a vibrating trough having a vertical side and a side which is inclined at 30°, for example, with the horizontal. The end of the trough remote from the hopper is adjacent the upper end of the chute (there being a slight clearance), and the articles to be packaged drop off that end of the trough and fall into the chute, all in predetermined position.

25 The mandrel has an escapement bar which, when the mandrel is in its up position, covers the lower end of the chute to hold the articles therein. When the mandrel starts its downward motion, the escapement bar opens the end of the chute, permitting a predetermined article-increment to drop through the mandrel.

30 Means timed with the mandrel may be provided to regulate at will the number of articles which will pass through the mandrel on each downward stroke thereof.

35 Means are preferably provided for regulating the rate at which articles are fed from the hopper, and such means will normally be adjusted so that articles emerge from the hopper slightly faster than they are packaged. Therefore, means may be included for taking off the overflow. The illustrated means is a distribution plate with adjustable wings.

40 Occasionally a broken article will be advanced along the trough, and as it is desirable that such an article not be packaged, means may be included for removing such article from the trough.

45 As illustrated herein, the machine will produce a dual product, that is, one having two parallel rows of packages. This means that there are two troughs, two inclined chutes and two mandrels, all side by side. The distance between each pair of elements is constant for all article configurations... .

50 Important objects of the invention are, there-

fore, to provide a machine which will attain all the above-mentioned advantages.

The above and other objects and advantages will appear more clearly from the following description taken with the accompanying drawings in which:

Fig. 1 is a side view of a machine embodying the invention;

Fig. 2 is a plan view of a part of the machine of Fig. 1, not showing the hopper and the ends of the vibrating troughs toward the hopper;

Fig. 3 is a sectional view taken on line 3-3 of Fig. 2, showing details of the article-feeding mechanism;

Fig. 4 is a sectional view taken on line 4-4 of Fig. 3, showing the mandrels at their lowermost position;

Fig. 5 is a side view showing a mandrel at its uppermost position;

Fig. 6 is a sectional view taken on line 6-6 of Fig. 3, showing details of the adjustable chutes;

Fig. 7 is a sectional view taken on line 7-7 of Fig. 1, showing details of the troughs and an example of means for removing broken articles from the troughs;

Fig. 8 is a perspective view showing the shape and mounting of the mandrels;

Fig. 9 is an enlarged sectional view taken on line 9-9 of Fig. 1, showing details of the article-feeding means from the hopper;

Fig. 10 is a sectional view taken on line 10-10 of Fig. 9; and

Fig. 11 is a sectional view taken on line 11-11 of Fig. 10.

Like reference characters denote like parts in the various views.

To refer at first particularly to Fig. 1 of the drawings, for a general understanding of the structure and its operation of the illustrated example of the invention, a pair of adjacent sealing rollers 10 and 12 have their respective, parallel shafts 14 and 16 horizontally supported in the same horizontal plane near the top of and between two vertical side plates 18 and 20 of a frame 22 having a horizontal base 24. The rollers 10 and 12 are positioned to abut each other at a vertical, tangential sealing location 25 therebetween.

Two parallel bars 26 and 28 are horizontally mounted on the top of the plates 18 and 20 to which they are attached at their forward ends. The rearward ends of the bars 26 and 28 are supported by a vertical post 30.

A first roll 32 of a web 34 of flexible, heat-sealable packaging material is mounted on a horizontal axis 36 on an arm 38 extending forward from one of the plates 18 and 20.

A second roll 40 of a web 42, which may be of material identical with that of the web 34, is mounted on a horizontal axis 44 supported beneath the bars 26 and 28 by a bracket 46 intermediate the frame 22 and the post 30.

A sprocket 46, which is rigidly mounted on the shaft 14 of the roller 10, is driven clockwise, as seen in Fig. 1, by an electric motor 48, sprockets 50 and 52 and a chain 54.

A gear 56 (Figs. 2 and 4) rigidly mounted on the shaft 14 of the roller 10 meshes with a similar gear 58 (Fig. 2) rigidly mounted on the shaft 16 of the roller 12. Thus, the rollers 10 and 12 are correspondingly rotated in opposite directions.

The roller 10 is provided with two series of recesses or pockets 60 and 62 peripherally spaced therearound, and the roller 12 may be similarly provided with two like series of recesses or

pockets 64 and 66. The pockets 60, 64 and 62, 66 correspond and are designed to register as the roller 10 and 12 are rotated. The pockets 60 and 62 are axially separated by a distance d , and the pockets 64 and 66 are likewise separated by the same distance. For reasons which will appear more clearly hereinafter, the distance d is a constant for all article sizes.

The webs 34 and 42 are passed downwardly through the sealing location 25 between the rollers 10 and 12, which are heated by means not shown to a temperature sufficient to render the webs plastic or tacky. The webs 34 and 42 are pressed together by the rollers 10 and 12 at the sealing location 25, and the heat and the pressure combine to seal the webs together, except at localities defined by the registering pockets 60, 64 and 62, 66.

The articles emanate from an open-bottomed downwardly-facing spout 67 of a hopper 68 mounted near the top of the post 30. The rearward ends, generally indicated at 69, of two horizontal, parallel troughs 70 and 72, are beneath and on either side of the hopper base 67. These troughs, having forward ends indicated generally at 71, are separated by spacers 74, 75 and 77.

The troughs 70 and 72 are open-topped, and have a modified V-shaped vertical cross-section (see Fig. 11). Thus, the troughs 70 and 72 have parallel vertical sides 76 and 78, respectively, affixed to the spacers 74, 75 and 77, and upwardly and outwardly inclined sides 80 and 82, respectively, joined to their corresponding vertical sides 76 and 78 at the bottom. The rearward ends 69 of the troughs 70 and 72 are closed by a vertical back plate 210.

Immediately below the hopper base 67 is a distribution plate 212, which is mounted, as by screws 214, on a horizontal strip 216, the screws 214 also serving to affix the strip 216 at its ends to the spacers 75 and 77.

The distribution plate 212 has vertical front and rear walls 218 and 220, respectively, the rear wall being secured, as by welding, to the front surface of the back plate 210.

The main part of the distribution plate 212 is in general horizontal, but is slightly higher along its longitudinal center 222 (see especially Fig. 11) than along its longitudinal edges 224 and 226, which respectively overhang the troughs 70 and 72 (Fig. 11).

An article guide 228 is secured as by welding to the front wall 218 of the distribution plate 212 and has wings 230 and 232 extending rearwardly from the wall 218 on either side of the hopper base 67 to a location near the back plate 210. The wings 230 and 232 correspond respectively to the edges 224 and 226 of the distribution plate 212.

Thus, the articles to be packaged emerge from the hopper base 67 onto the distribution plate 212 and substantially equally onto both sides of the high center 222 thereof. The plate 212 is vibrated (as will be described) and such vibration (plus gravity) causes the articles to proceed outwardly away from the center 222, and the wings 230 and 232 (because of the pressure of succeeding articles) guide the articles rearwardly, until they pass through openings 234 and 236 (see especially Fig. 9) defined by the back plate 210, and the wings 230 and 232, respectively, and slide over the edges 224 and 226 of the distribution plate 212, respectively, and fall into the corresponding troughs 70 and 72.

The rate of flow of articles into the troughs

70 and 72 is dependent upon the size of the articles and the size of the corresponding openings 234 and 236. Therefore, the wings 230 and 232 are made adjustable, as by bending them about axes 238 and 240, respectively (Fig. 11). Thus may the size of the openings 234 and 236 be adjusted to accommodate articles of varying sizes and to regulate the rate of article flow.

The distribution plate 212, the back plate 210, the strip 216, the walls 218 and 220, the guide 228, etc. appear also in Fig. 1, but are not numbered thereon, for the sake of clarity.

The V-shaped configuration of the troughs 70 and 72 causes the articles to assume definite positions therein. For example, the illustrated articles (Figs. 3, 5-7) are tablets 84 which will flop over with their large dimensions parallel to the inclined sides of the troughs 70 and 72 (see Fig. 7). If the articles were elongated capsules, they would lie in the bottom of the troughs with their long dimensions lengthwise of the trough thereof.

The spacer 74 holds the troughs 70 and 72 so that the articles will be separated by a distance slightly more than d (see above).

Good results are attained with troughs in which the inclined sides 80 and 82 make an angle of about 30° with the horizontal, as illustrated in Fig. 7.

At any rate, the spacers 74, 75 and 77 are mounted upon a vibrating table, indicated generally at 86 (Fig. 1) having one end affixed to the post 30 and carried upon the bars 26 and 28, as by blocks 88 and 90. The vibrating table 86, which is actuated by a solenoid 92, vibrates the troughs 70 and 72 to throw articles therein up in the air at, for example, a 15° angle to the left. Thus, with each vibration the articles will fall back against the troughs at a location slightly closer to the forward ends 71 of the troughs 70 and 72. The vibrations are very slight and are not violent enough to disturb the alignment of the articles in the troughs.

The distribution plate 212 (including its front and rear walls 218 and 220) and the guide 228 with its wings 230 and 232 are likewise vibrated, by reason of these parts being mounted on the strip 216 carried rigidly on the spacers 75, 77.

As the articles proceed along the troughs 70 and 72 toward the forward end 71 thereof, they line up in single file in their characteristic predetermined positions.

There is often quite a bit of dust (from the articles) in the troughs, and occasionally a broken article comes along. It is desirable that such dust or broken article not find its way any further than the forward end 71 of the troughs 70 and 72. Accordingly, an escape for such material is provided shortly before it reaches the forward end 71 of the troughs 70 and 72. Each trough is provided with such an escape or diverter, and the diverter for the trough 70 will now be described.

Near the forward end 71 of the trough 70 is a slot 94 through the vertical side 76, the slot extending a predetermined distance lengthwise of the side 76. The bottom of the slot 94 is at the joint between the inclined side 80 and the vertical side 76, and is arranged to form a smooth downward passage for flow of material through the slot. A vertically adjustable plate 96 covers the top of the slot 94 and is connected to the vertical side 76 by screws 98, through corresponding, vertically elongated slots (not shown).

Thus, the effective height of the slot 94 is determined by the setting of the screws 98 in their elongated slots, and depending upon that setting, material up to a given maximum height can escape through the slot 94. A broken tablet 84b is shown in position to fall through the slot 94.

The trough 72 is provided with a similar diverter, having a slot 100, a plate 102, screws 104 and elongated slots 106 (see Figs. 1, 3 and 7).

For the type of tablet shown in the drawings, it has been found not to be feasible to try to set the plates 96 and 102 to give escape to broken tablets which retain more than about 75% of their original thickness.

A dust and broken article bin 109 is positioned to catch the material which passes through the slots 94 and 100.

Positioned with their upper ends adjacent and aligned with the forward ends 71 of the troughs 70 and 72 are a pair of parallel, stationary chutes 108 and 110 of rectangular transverse section. The chutes 108 and 110 are inclined downwardly from their respective troughs 70 and 72 at an angle of 45° , for example.

The chutes 108 and 110 have a common base portion 112, comprised of a bottom plate 114 and a central block 116 of rectangular, transverse section projecting upwardly from the center of the plate 114, and extending substantially the entire length thereof. The thickness of the block 116 is preferably the same as the spacing of the troughs 70 and 72, i. e. slightly greater than d , the distance separating the two series of pockets on the rollers 10 and 12.

As shown, the plate 114 and the block 116 are integrally formed, but they may be made separately if desired.

The upper surface of the bottom plate 114 and one of the vertical surfaces of the block 116 form two intersecting sides of the rectangular chute 108, and the upper surface of the bottom plate 114 and the other vertical surface of the block 116 form two intersecting sides of the rectangular chute 110.

The top side of the chute 108 is defined by a vertically adjustable guide rail 118 which is secured to the corresponding vertical surface of the block 116 by screws 120 passing through vertically elongated slots 122 in the guide rail 118.

The rail 118 has its lower edge parallel to the upper surface of the plate 114, and is separated from the corresponding vertical surface of the block 116 by a collar 124 on each screw 120, between the rail 118 and the block 116. Such separation is preferably a distance equal to about one-half the average lateral dimension of the articles (as they come from the trough 70) which the machine is to be called upon to package.

By loosening the screws 120, the guide rail 118 may be moved up or down to position the same with its lower edge separated from the plate 114 by a distance equal to the thickness of the articles to be packaged.

The chute 110 has a similar vertically adjustable guide rail 126, with similar screws 128, vertical slots 130 and collars 132.

The outer side of the chute 108 is defined by a laterally adjustable guide rail 134 which is secured to the upper surface of the plate 114 by screws 136 and nuts 138.

The screws 136 pass through laterally elongated slots 140 in the lateral guide rail 134, which has its inner edge parallel to the corresponding vertical surface of the block 116.

By loosening the screws 136, the guide rail 134

may be moved closer to or further from the block 116 to position the same with its inner edge separated from the block 116 by a distance equal to lateral dimension of the articles to be packaged.

The chute 116 has a similar laterally adjustable guide rail 142, with similar screws 144, nuts 146 and laterally elongated slots 148.

The guide rails 118, 126, 134 and 142 are shown in Fig. 6 properly adjusted for the tablets 84, the dimensions of the chutes 108 and 110 being defined, respectively, by the plate 114, the block 116 and the guide rails 120 and 134, and the plate 114, the block 116 and the guide rails 126 and 142.

Thus, when articles reach the forward end 71 of the troughs 70 and 72 in predetermined position, they fall gently into the chutes 108 and 110 and slide down to the lower ends thereof, lined up in single file as shown by the tablets 84 in Figs. 3 and 5.

In the normal operation of the machine, as aforesaid, the troughs 70 and 72 deliver articles slightly faster than they are packaged, so that articles line up in the chutes 108 and 110 all the way to the upper ends thereof. Therefore, some 25 articles will fall out between the troughs 70 and 72 and their respective chutes 108 and 110, at the forward end 71 of the former. This overflow is caught in an overflow bin 150 positioned beneath the point of overflow. When enough articles are in the bin 150, the operator may pour them back into the hopper 68.

The upper ends of the chutes 108 and 110 are held in place by a bracket 152, the lower end of which is secured to the bars 26 and 28, as at 154. The lower ends of the chutes 108 and 110 are mounted on a bracket 155 which is secured to the bars 26 and 28.

Positioned at the lower ends of the chutes 108 and 110 are two mandrels 156 and 158, respectively, directly above the sealing location 25 between the rollers 10 and 12, which are vertically reciprocable, by means which will be described, to spread the webs 34 and 42 into the pockets. The mandrel 156 thus pushes one of the webs into the pockets 66 on the roller 12 and the other web into the pockets 62 on the roller 10, and the mandrel 158 pushes one of the webs into the pockets 64 on the roller 12 and the other web into the pockets 68 on the roller 10. The mandrels 156 and 158 are timed, by means which will be described, to perform said spreading action just as corresponding pockets are coming together.

The mandrels 156 and 158 have extensions 160 and 162, respectively, which will be called escapement bars hereinafter. The escapement bars 160 and 162 are positioned so that when their respective mandrels 156 and 158 are at the upper ends of their reciprocating strokes, the escapement bars 160 and 162 will cover the lower ends of the chutes 108 and 110, respectively. As the mandrels 156 and 158 start downward to spread the webs as aforesaid, the escapement bars 160 and 162 likewise move downward, uncovering the ends of their chutes to permit articles to slide over the tops of the bars 160 and 162, and drop into the packages being formed in the webs by the mandrels 156 and 158. The mandrels then move upwardly and the bars 160 and 162 once again cover their chutes 108 and 110 to prevent articles from dropping out.

The top edges of the bars 160 and 162 are preferably inclined as at 164 at the same inclination as the chutes 108 and 110, to ease the path of the articles thereover.

The mandrels 156 and 158 are mounted as by screws 164 on a common vertical post 166 therebetween. The post 166 is suitably secured to an outrigger plate 170 which extends crosswise of the machine. Further vertical posts 172 and 174 project upwardly from the bars 26 and 28, respectively. The outrigger plate 170 has a vertical tubular bushing or guide 176 at one end, and the guide 176 surrounds the post 174 in slidable engagement therewith. The other end of the plate 170 has a vertical guide cage 178 which surrounds the post 172 on three sides (see Fig. 2).

The shaft 16 carries a cam 180 rotatable therewith, and a cam follower 182 which is carried by the outrigger plate 170 is positioned in engagement with the cam 180. As illustrated, the cam 180 has one indentation 184, so that the cam follower 182, and hence the mandrels 156 and 158 will drop downwardly to spread the webs 34 and 42 once for each revolution of the rollers 10 and 12. More indentations can be provided on the cam 180, if desired, for faster action.

The indentation 184 is positioned so that the mandrels 156 and 158 will perform their downward stroke only when pockets on the rollers 10 and 12 are coming together.

The mandrels are shown in their up position in Fig. 5 and in their down position in Fig. 3.

The entire action of the outrigger plate 170 is upon the bushing 176, the cage 178 merely serving to maintain the outrigger plate 170 in proper alignment.

Vertically adjustable counting pins 186 and 188 correspond to the mandrels 156 and 158, respectively, to regulate the number of articles which will fall over the escapement bars 160 and 162, as aforesaid. The pins 186 and 188 are in freely slidable relationship in vertical tubular guides 190 and 192, respectively, which are secured to the post 166 on either side thereof. The pins 186 and 188 are prevented from falling through the guides 190 and 192 by collars 194 and 196, respectively, which rest upon the tops of the guides 190 and 192. Thus the lower ends of the pins 186 and 188 are positioned directly above and near the lower ends of their respective chutes 108 and 110, and the pins 186 and 188 follow the movement of the mandrels 156 and 158. When the mandrels are in their up position, the escapement bars 160 and 162 block their chutes 108 and 110, as aforesaid, and the lower ends of the pins 186 and 188 are above the columns of articles in the chutes. Some time after the mandrels start their downward stroke, the lower ends of the pins 186 and 188 intersect the article columns in their chutes 108 and 110, to interrupt the flow of articles past the bars 160 and 162. The angular position of the pins 186 and 188 and their respective guides 190 and 192 determines the number of articles to be counted into the packages being formed.

Therefore, if it is desired to put two articles in each package, the pins 186 and 188 will be adjusted angularly by means of their collars 194 and 196 to increase the counting position.

Sometimes it is desired to stop the flow of articles while the rollers 10 and 12 are still running. To accomplish this end, a feeding trigger or lever 200 is provided, by means of which the outrigger plate 170 may be raised so that the cam follower 182 is out of contact with the cam 180. The lever 200 is pivotally mounted upon the plate 170, as at 201, and has a cam-like edge 202 which bears against the bar 28 to interpose an increasing radius between the pivot 201 and the bar 28 as the lever 200 is moved clockwise, as

seen in Fig. 4. Thus, as movement in that direction takes place, the outrigger plate 170 is raised, and the cam follower 182 is lifted out of engagement with the cam 180.

At the same time, the mandrels 156 and 158, and their escapement bars 160 and 162, are also raised. The bars 160 and 162 are sufficiently long vertically so that when the lever 200 is lowered, the articles cannot pass underneath the bars 160 and 162.

The position of the outrigger plate 170 with the lever 200 in its downward position is shown by the dotted lines in Fig. 4.

To summarize the invention by way of a brief statement of the operation of the illustrated embodiment of the machine, articles are fed into the troughs 70 and 72 from the hopper 68, and advanced along the troughs by vibration to the upper ends of the stationary chutes 108 and 110, which are adjustable in cross-sectional configuration to accommodate articles of varying sizes and shapes. The chutes are inclined downwardly, and the articles line up single file in predetermined position in the chutes. Article egress from the chutes is prevented by the escapement bars 160 and 162 when the corresponding vertically reciprocating mandrels 156 and 158 are at the upper ends of their strokes. When the mandrels move downwardly to spread the webs into the pockets, a number of articles, predetermined by the pins 186 and 188, fall over the tops of the escapement bars 160 and 162 to enter the packages being formed. A package 210 containing a tablet 84 is shown in Fig. 3 just after emerging from the sealing location 25.

Many modifications and variations will be apparent or will occur to those skilled in the art, and it is not intended to limit the invention to the specific embodiment set forth by way of example, except as may be defined by the following claims.

I claim:

1. In a high speed continuous feed packaging machine having a pair of sealing rollers with peripherally spaced matched article-defining pockets thereon, a pair of spaced webs, means for continuously feeding said webs between said rollers, vertical reciprocating means for spreading said webs into said pockets to form packages and stationary adjustable dimensioned article feed means for depositing articles into said formed packages.

2. In a high speed continuous feed packaging machine having a pair of sealing rollers with peripherally spaced matched article-defining pockets thereon, a pair of spaced webs, means for continuously feeding said webs between said rollers, a movable mandrel for spreading said webs into said pockets to form article-receiving packages, and stationary feed means adjustable to handle various sizes of articles and operative to feed articles to said packages for deposit therein.

3. In a machine for continuously forming article-containing packages of two webs of flexible packaging material, a pair of cooperating sealing rollers having a series of peripherally spaced article-defining pockets to receive the articles to be packaged, means for feeding the webs between the rollers, a reciprocable mandrel operable in timed relation with the rollers and cooperatively associated with the pockets to spread the webs to conform thereto, and a relatively stationary chute to supply articles to the pockets between the webs, the chute being adjust-

able to accommodate articles of varying sizes and shapes.

4. In a machine for enclosing articles between two webs of flexible packaging material, including a pair of sealing rollers having matched article-defining pockets on their peripheries, a reciprocable mandrel operable in timed relationship with the rollers to spread the webs into the pockets and form packages, relatively stationary article-feeding member for depositing articles in said packages, and means for adjusting the cross-sectional area and shape of said member for accommodating articles of various shapes and sizes.
5. The invention set forth in claim 4 wherein said mandrel is hollow so as to permit articles to pass therethrough to enter the packages.
6. In a machine for forming article-containing packages of webs of flexible packaging material, in combination, a pair of matched counter-rotating sealing rollers abutting each other at a tangential sealing location and having article-defining pockets thereon, a stationary filling chute of adjustable cross-sectional area inclined to advance a column of articles by gravity in predetermined position toward said sealing location, and a hollow mandrel mounted to reciprocate above said sealing location and cooperatively associated with said article-defining pockets for forming packages by spreading the webs therein, said mandrel having an escapement bar which alternately blocks and opens the lower end of said chute.
7. The invention set forth in claim 6 wherein the inclination of said chute is about 45°.
8. In a machine for forming article-containing packages of webs of flexible packaging material, a pair of counter-rotating sealing rollers having matched article-defining pockets thereon, a reciprocable mandrel operable in timed relationship with said rollers and cooperatively associated with said article-defining pockets for forming packages of predetermined volumetric characteristics, and an adjustable article-feeding member which is stationary relative to the reciprocal mandrel for depositing articles in the packages formed by said mandrel and said article-defining pockets.
9. In a machine for forming article-containing packages of webs of flexible material, in combination, a pair of counter-rotating sealing rollers abutting each other at a tangential sealing location, and having matched article-defining pockets thereon, a hollow vertically reciprocable mandrel cooperatively associated with said pockets to spread the webs thereinto at one end of its stroke to form open packages, means for advancing a column of articles toward said sealing location, and an escapement bar reciprocable with said mandrel alternately to block and to permit the passage of articles from said advancing means, the latter when the mandrel is at said end of its stroke.
10. The invention set forth in claim 9 which further includes a reciprocable outrigger plate on which the mandrel is mounted, and guides for said outrigger plate.
11. The invention set forth in claim 9 wherein means reciprocable with said mandrel is included to regulate the number of articles which will pass from said advancing means when the escapement bar is in position to permit such passage.
12. The invention set forth in claim 9 which further includes a reciprocable outrigger plate on

11

which the mandrel is mounted, a cam rotatable with one of said rollers, a cam follower slidably engaging said cam, means connecting the cam follower to said outrigger plate to reciprocate said outrigger plate, and guides for said outrigger plate.

13. The invention set forth in claim 12 in which a lever is provided by which said outrigger plate can be shifted and the cam follower removed from engagement with the cam to halt the reciprocation of the mandrel and permanently block the passage of articles from said advancing means.

14. In a machine for forming article-containing packages of webs of flexible material, in combination, a pair of counter-rotating sealing rollers abutting each other at a vertical, tangential sealing location, and having matched article-defining pockets peripherally spaced therearound, a hollow vertically reciprocable mandrel positioned above said sealing location to spread the webs into said pockets at the lower end of its stroke to form open packages, an inclined chute of adjustable cross-sectional area to advance a column of articles toward said sealing location by gravity, and an escapement bar reciprocable with the mandrel alternately to prevent articles from falling and to permit articles to fall from the lower end of said chute, the latter when the mandrel starts its downward stroke.

15. In a machine for forming article-containing packages of webs of flexible packaging material, a pair of counter-rotating sealing rollers having matched article-defining pockets thereon, a reciprocal mandrel operable in timed relationship with said rollers and cooperatively associated with said article-defining pockets for forming packages of predetermined volumetric characteristics, a non-reciprocal chute in which articles are advanced toward said sealing location in predetermined position, and means for adjusting the cross-sectional area and shape of said chute to accommodate articles of varying sizes and shapes.

16. In a machine for forming article-containing packages of webs of flexible material, and in which the webs are spread into matched article-defining pockets on a pair of counter-rotating rollers abutting each other at a tangential sealing location by a reciprocable mandrel, a relatively stationary chute in which articles are advanced toward said sealing location in predetermined position, said chute comprising a base portion having a vertical and a lateral dimension, to form two adjacent sides of the chute, a vertically adjustable guide rail positioned above the lateral dimension of said base portion and having its lower edge parallel thereto, and a laterally adjustable guide rail having an edge facing and parallel to the vertical dimension of said base portion.

17. The invention set forth in claim 15 wherein said chute is inclined and the articles are fed therethrough by gravity.

18. The invention set forth in claim 15 wherein said chute is inclined at an angle of approximately 45° and the articles are fed therethrough by gravity.

12

19. In a machine for forming article-containing packages of webs of flexible material, and in which the articles advance toward the sealing location in predetermined position in an inclined chute, a supply hopper, a horizontal vibrating trough to transport articles to be packaged from said hopper to the upper end of said chute in said predetermined position, said trough being substantially V-shaped in vertical section and means for the escape of article dust and broken articles from said trough, said means including a slot lengthwise of the trough and near the bottom of the V.

20. In a machine for forming article-containing packages of webs of flexible material, and in which the articles advance toward the sealing location in predetermined position in an inclined chute, a supply hopper, a horizontal vibrating trough to transport articles to be packaged from said hopper to the upper end of said chute in said predetermined position, said trough having a vertical side and an inclined side joined to said vertical side at the bottom and means provided for the escape of article dust and broken articles from said trough, said means including a slot lengthwise and near the bottom of the trough, and a vertically adjustable plate covering an adjustable portion of the slot.

21. A machine for continuously forming product-containing packages of two webs of flexible packaging strips, a pair of cooperating sealing rollers having a series of peripherally spaced product-defining pockets to seal the product to be packaged, means for feeding said webs between said rollers, a movable mandrel operable in timed relation with said rollers and cooperatively associated to said pockets to spread the webs to conform thereto, and relatively stationary means for feeding the product to said pockets between said webs.

22. A packaging machine comprising a pair of cooperating rollers mounted with their axes horizontal and having a series of peripherally spaced commodity-defining pockets to receive the product to be packaged, means for feeding two independent webs downwardly between the cooperating rollers, a mandrel which reciprocates vertically and is adapted to enter the pockets in succession and spread the webs to form envelopes for the product, and non-reciprocating means for feeding a stream of product between the webs, without interfering with the operation of the reciprocating mandrel.

JOHN H. STROOP.
